APPARATUS FOR DEMONSTRATING THE CUSHIONING EFFECT OF CARPET OR RUG LININGS

Jerome E. Cook, Bronxville, N. Y., assignor to Bigelow-Sanford Carpet Co. Inc., Thompsonville, Conn., a corporation of Massachusetts

Application April 14, 1934, Serial No. 720,562

4 Claims. (Cl. 35—50)

This invention relates to an apparatus for demonstrating the cushioning effect of linings or underlays for carpets and rugs, and is more especially directed to a device of this general character by which the relative value of different linings or underlays may be readily ascertained.

It is now the general practice to provide a lining or an underlay for carpets and rugs and inasmuch as the purchaser desires to exercise his or her tastes along these lines in selecting the character of lining or underlay, the present invention provides a ready, compact and portable means for making such selection.

In accordance with the general purpose of the present invention a series of carpet or rug linings or underlays, preferably in strip form, are supported by frame work and associated therewith is a demonstrating member, which, when in demonstrating position extends from the frame structure and has secured along the outer edge of such demonstrating member a piece of carpet with its inner end free so that when one of the linings or underlays is removed from its initial supporting position on the frame structure, a portion of the lining or underlay will rest upon the tread surface of the demonstrating member and beneath the inner loose portion of the carpet or rug, so that the feel or tread of the carpet or rug either with or without the lining or underlay may be readily ascertained.

The invention and novel features thereof will best be made clear from the following description and accompanying drawing of one good form thereof.

35 In the drawing:—

Fig. 1 is a perspective view showing the demonstrating apparatus with the parts in non-demonstrating position;

Fig. 2 is a similar view showing the demonstrating member moved to its demonstrating position with the strip of carpet secured along the outer edge of the demonstrating member;

Fig. 3 is a similar view showing one of the linings or underlays taken from its initial supported position with the free end of the carpet turned upward to permit the lower end portion of the lining or underlay to rest upon the tread surface of the demonstrating member; and

Fig. 4 is a similar view showing the parts as they appear during the actual demonstration of the cushioning effect or feel of the carpet either with or without the lining or underlay.

The frame structure may be of any appropriate design and as shown consists of the side members 55 1 provided with bearings 2 for the support of a

number of different kinds of linings or underlays, each of which may be of appropriate size for the purpose intended.

Each of the linings or underlays is secured to a rod or bar 3 at its upper edge and from which it depends or hangs while the end portion of the bars or rods may be supported in the bearings 2 of the frame structure. The essentials in this respect are that the series of linings or underlays may be arranged in the frame structure for ready inspection or selection and then removed therefrom, as will presently appear.

The demonstrating member 4 is shown in the present instance of the invention as secured to the lower part of the frame structure by hinges 5 whereby it may be turned outwardly into demonstrating position, as indicated in Fig. 2. When thus turned to demonstrating position, as indicated by Fig. 2, the demonstrating member has a tread surface 6 exposed which may appropriately be of a plain surface, such as might be present in the floor of a room or other structure.

Secured to the demonstrating member 4 along its outer edge when in demonstrating position, is a strip of carpet 7 which may be attached to the demonstrating member or the tread surface thereof by fastenings 8, thus leaving the inner edge 9 of the carpet loose, the construction being such that when the demonstrating member or door is closed, as in Fig. 1, the strip of carpet 20 will hang from its fastenings along the upper inner edge of the door. It may be desirable at times to attach the edge of the carpet to the free edge of the door or demonstrating member by removable fastenings, so that the strip of carpet 7 may be changed from time to time.

As hereinbefore noted, the lining or underlay to be demonstrated is taken from its normal supporting position, as indicated in Figs. 1 and 2, and transferred to a lower position at the front 40 of the frame structure, as indicated in Figs. 3 and 4, so that the lower free edge of the lining or underlay may rest upon the tread surface of the demonstrating member. As one convenient means for effecting this purpose the side members 1 of the frame structure are provided with lower or demonstrating bearings 10, adapted to receive any one of the supporting rods or bars 3 to which one of the linings or underlays is secured, and by reason of the location of the bearings 10 the free edge of the lining or underlay 11 will rest upon the tread surface 6 of the demonstrating member, as indicated more clearly in Figs. 3 and 4.

With the support for the lining or underlay 55

placed in the demonstrating bearings 10 and the lining or underlay hanging from its supporting bar or rod, the attendant or salesman will turn back the loose inner edge 9 of the carpet 7, as indicated in Fig. 3, to permit the lower loose end portion of the lining or underlay to rest upon the tread surface of the demonstrating member. The attendant will then turn the loose edge of the carpet back to its original position to 10 overlite the lower portion of the lining or underlay, as indicated in Fig. 4, wherein it will be noted that the inner or loose portion of the carpet will rest upon the lower end portion of the lining or underlay while the outer portion of the carpet will rest upon the tread surface, with the result that by standing on the carpet with one 15 foot on that portion of the carpet that overlies the lining or underlay and the other foot on that portion of the carpet that rests upon the tread surface, one may at once detect the difference in 20 feel between the two portions of the carpet.

The details of the apparatus may be varied within wide limits, but the structure described presents a good compact and portable means for 25 demonstrating the cushioning effect or feel of any one of a series of different linings or underlays.

What is claimed is:—

1. In an apparatus for demonstrating the cushioning effect of lining or underlays for carpets and rugs, the combination of a frame structure, 30 a demonstrating member extending from the lower part of the frame structure when in demonstrating position and having a tread surface, a strip of carpet secured to the outer edge of the demonstrating member with its inner edge free, 35 and demonstrating supports on the frame structure for a carpet or rug lining to which a carpet or rug lining may be transferred so that its lower portion may rest upon the tread surface of the demonstrating member under the inner free edge 40 of the strip of carpet.

2. In an apparatus for demonstrating the cushioning effect of lining or underlays for carpets and rugs, the combination of a frame structure, 45 a demonstrating member extending from the

lower part of the frame structure and having a tread surface, a strip of carpet secured to the outer portion of the demonstrating member and resting on the tread surface thereof with its inner edge free, and means carried by the frame structure for supporting a carpet or rug lining with its lower portion on the tread surface of the demonstrating member so that the strip of carpet may have its inner portion rest upon the lining and its outer portion on the tread surface 10 of the demonstrating member.

3. In an apparatus for demonstrating the cushioning effect of linings or underlays for carpets and rugs, the combination of a frame structure, 15 a demonstrating member extending from the frame structure when in demonstrating position and having a tread surface, supports on the frame structure for sustaining a carpet or rug lining or underlay in a demonstrating position with the lower portion of the lining or underlay resting on 20 a part of the tread surface of the demonstrating member, and a strip of carpet secured along the outer portion of the tread surface of the demonstrating member with its inner edge free that it may be turned onto the lining or underlay at 25 its inner portion while its outer portion rests upon the tread surface of the demonstrating member to permit demonstration of carpet feel with and without the lining or underlay.

4. In an apparatus for demonstrating the cushioning effect of linings for carpets and rugs, the combination of a frame structure, a demonstrating door hinged at its lower edge to the frame structure that it may be turned downwardly into demonstrating position, a strip of carpet secured along its upper edge to the inner surface of the door so that when the door is downwardly turned into demonstrating position the edge of the carpet adjacent the frame structure will be free, and demonstrating supports at the front of 35 the frame structure adapted to support a lining or underlay for carpets or rugs so that the lower part of the lining may be placed beneath the free edge of the strip of carpet on the door.
